UNITED STATES PATENT OFFICE.

PEDER MYR HOLM, OF VOLGA, SOUTH DAKOTA, ASSIGNOR OF ONE-HALF TO JULIUS MARTINSON, OF VOLGA, SOUTH DAKOTA.

BARREL-TRUCK.

1,018,260.

Specification of Letters Patent. Patented Feb. 20, 1912.

Application filed June 12, 1911. Serial No. 633,000.

To all whom it may concern:

Be it known that I, PEDER MYR HOLM, a subject of the King of Norway, residing at Volga, in the county of Brookings and State 5 of South Dakota, have invented certain new and useful Improvements in Barrel-Trucks, of which the following is a specification.

The present invention involves improvements in that type of trucks designed particularly for lifting and moving barrels from one place to another and embodying a suitable wheeled supporting frame, a runner having lifting arms to engage the barrel or other heavy article, and suitable means for raising and lowering the runner.

For a full understanding of the present invention, reference is to be had to the following description and to the accompanying drawings, in which—

20 Figure 1 is a vertical sectional view, certain parts being shown in elevation, illustrating a truck embodying the essential features of the invention; Fig. 2 is a horizontal section taken on the line 2—2 of Fig. 1, looking downwardly; Fig. 3 is a rear elevation; Fig. 4 is a detail plan view of the lifting lever and dog mounted thereon; Fig. 5 is a detail section on the line 5—5 of Fig. 1; Fig. 6 is a detail sectional view showing the 25 withdrawn position of the locking catch carried by the runner.

Throughout the following detail description and on the several figures of the drawings, similar parts are referred to by like 30 reference characters.

In the drawings, 1 denotes the frame of the truck which is supported upon suitable wheels 2, the side sills of the frame terminating at one end in handles 3. A vertical frame 4 extends upwardly from the wheeled 35 frame 1 between the ends of the latter and between the sides of the frame 4 is the vertical standard 5, the latter being of T-shape in cross section and its central rib or web 5' being toothed vertically or longitudinally thereof, as shown at 6. On the standard 5 are also provided, at one side of the member 5', a plurality of notches 5".

A runner 7 having a vertical groove of 40 somewhat T-shape to conform with the cross sectional shape of the standard 5 is mounted upon said standard for vertical movement and is provided, at opposite sides thereof with pairs of pivot lugs 8 between which

are pivoted the lifting arms 9. Each of the 55 arms 9 carries a gripping block 10 at one end while at its other end it is provided with a plurality of teeth 11. A flat spring 12 is secured to the front side of the runner 7 and the opposite ends of said spring bear against 60 the inner curved sides of the arms 9, normally tending to force said arms apart. As apparent from the drawings, the arms 9 are pivoted between their ends to the lugs 8 and the rear toothed end portions of the arms 65 are adapted to be engaged by the pawls 13 which are pivoted to the runner 7 and which, when engaging the teeth 11, will hold the arms 9 in operative engagement with the object which is to be lifted and moved by 70 means of the truck.

The runner 7 is adapted to be raised by a lifting lever 14 which is provided at its inner end with a yoke 15 pivotally connected at its opposite sides to the opposite sides of 75 the runner 7 as shown at 15'. The yoke 15 comprises complementary plates secured to the opposite sides of the inner end of the lever 14 and pivotally mounted between projecting portions of the plates forming the 80 yoke is the lifting dog 16 arranged to engage the teeth 6 of the standard 5 in order to coöperate with the lever 14 to lift the runner 7 by a step by step movement as said lever 14 is raised and lowered by the operator. A pull rod 17 connected at one end to the dog 16 is attached at its opposite end to a pivoted handle 18 carried by the lever 14. The operator can readily withdraw the 85 dog 16 from coöperation with the standard 90 5 by manipulation of the parts 17 and 18. A coiled spring 19 interposed between the dog 16 and a bracket 20 tends to hold the dog 16 engaged with the standard 5.

The runner 7 is locked as it is raised by 95 the lever 14 and dog 16 by means of a sliding catch 21 normally forced into engagement with the notches 5" by means of the spring 22 said catch being mounted between the sides of a yoke 23 secured to the runner. 100 A hand rod is connected to the catch 21 and formed with a flat handle 24 which normally operates through a vertical slot in the outer end of the yoke 23. When the handle 24 is operated to withdraw the catch 21, as 105 shown in Fig. 6, said handle may be turned so that its flat body is arranged transversely with respect to the slot in the outer end of

the yoke 23, whereby the catch 21 will be held in its withdrawn position, as shown in Fig. 6, this being a desired adjustment preliminary to lowering the runner 7. The gripping surfaces of the blocks 10 are preferably serrated or roughened to increase their gripping action.

It will be apparent that the invention is used by moving the truck toward the barrel 10 or other object, the arms 9 being thus engaged with the object and locked in such engagement by the pawls 13. By successively lowering and raising the lever 14, the barrel will be raised by the arms 9, until it reaches a suitable elevation, whereupon the runner 7 will be held at its adjustment by the catch 21 which must be released previous to lowering the runner for depositing the object supported by the arms 9 at 20 its proper place. In order to facilitate simultaneous adjustment or movement of the arms 9, the rear ends of said arms are connected by the links 9', with one of which is formed a suitable handle 9'' adapted to be 25 readily pulled so as to correspondingly move the arms 9 toward and from one another.

It is contemplated also to provide readily operable means for simultaneously disengaging the pawls 13 from the teeth 11 of 30 the arms 9 for which purpose said pawls are connected by a toggle joint 13', the pivot connecting the adjacent ends of the members of said joint being slideable in a slot 25 on a bracket 26 projecting from the member 7. 35 A vertical pull rod 27 is connected by a link 28 with one of the members of the toggle joint 13 and the pivotal member 27', connecting the link 28 to the pull rod 27 is slideable vertically in the slot 28' which latter is provided in a vertical extension of the bracket 26. The rod 27 is formed with a notch 29 near its upper end in which is adapted to be engaged a locking rod 30 movable by a hand lever 31. It will be apparent that when the lever 31 is depressed 40 the rod 30 will be engaged with the rod 27 so that by lowering the lever 14, the joint 13' will be forced outwardly on the bracket 26 and the pawls 13 simultaneously disengaged from the teeth 11.

Having thus described the invention, what is claimed as new is:

1. In a barrel truck, the combination of a wheeled frame, a vertical standard carried thereby and having a vertical toothed portion, a runner movably mounted upon said standard, a lever pivoted to said runner, a lifting dog carried by said lever to engage the toothed portion of the standard to raise the runner by a step by step movement, lifting arms pivoted between their ends to opposite sides of the runner, a spring secured to one side of the runner and having its ends engaging the front end portions of the lifting arms, normally tending to force

the latter apart, gripping means carried by the front ends of the lifting arms, and pawls coacting with the rear ends of the lifting arms to lock the latter in engagement with an object. 70

2. In a barrel truck, the combination of a wheeled frame, a vertical standard carried thereby and having a vertical toothed portion, a runner movably mounted upon said standard, a lever pivoted to said runner, a lifting dog carried by said lever to engage the toothed portion of the standard to raise the runner by a step by step movement, lifting arms pivoted between their ends to opposite sides of the runner, a spring secured 75 to one side of the runner and having its ends engaging the front end portions of the lifting arms, normally tending to force the latter apart, gripping means carried by the front ends of the lifting arms, the rear ends 80 of the lifting arms being toothed on their inner sides, pawls pivoted to the runner between the lifting arms and having their outer ends engageable with the teeth of the latter to lock the same in engagement with 85 an object, a catch slidably mounted on the runner, the standard having notches adapted to be engaged by said catch, a spring normally holding the catch in engagement with the standard, and a handle for said catch 90 movable into positions permitting free engagement of the catch with the standard or holding the catch temporarily disengaged from the standard. 95

3. In a barrel truck, the combination of a wheeled frame, a vertical standard carried thereby and having a vertical toothed portion, a runner movably mounted upon said standard, a lever pivoted to said runner, a lifting dog carried by said lever to engage 100 the toothed portion of the standard to raise the runner by a step by step movement, lifting arms pivoted between their ends to opposite sides of the runner, a spring secured to one side of the runner and having its ends 105 engaging the front end portions of the lifting arms, normally tending to force the latter apart, gripping means carried by the front ends of the lifting arms, pawls coacting with the rear ends of the lifting arms to lock the latter in engagement with 110 an object, and means connecting the rear ends of the lifting arms for simultaneously moving the same toward and from one another. 115

4. In a barrel truck, the combination of a wheeled frame, a vertical standard carried thereby and having a vertical toothed portion, a runner movably mounted upon said standard, a lever pivoted to said runner, a lifting dog carried by said lever to engage the toothed portion of the standard to raise the runner by a step by step movement, lifting arms pivoted between their ends to opposite sides of the runner, a spring secured 125 to one side of the runner and having its ends engaging the front end portions of the lifting arms, normally tending to force

to one side of the runner and having its ends engaging the front end portions of the lifting arms, normally tending to force the latter apart, gripping means carried by the front ends of the lifting arms, pawls co-

acting with the rear ends of the lifting arms 10
engaging said toggle joint to simultaneously dis-

In testimony whereof I affix my signature
in presence of two witnesses.
